INVENTOR:

UNITED STATES PATENT OFFICE.

FREDERICK T. FEAREY, OF NEWARK, AND JOHN SPEICHER, OF JERSEY CITY, NEW JERSEY, ASSIGNORS TO THE NEWARK DISTRICT TELEGRAPH COMPANY, OF NEW JERSEY.

FIRE-ALARM SYSTEM.

SPECIFICATION forming part of Letters Patent No. 443,478, dated December 23, 1890.

Application filed July 30, 1889. Serial No. 319,180. (No model.)

To all whom it may concern:

Be it known that we, FREDERICK T. FEAREY, residing at Newark, Essex county, New Jersey, and JOHN SPEICHER, residing at Jersey City, in the county of Hudson and State of New Jersey, citizens of the United States, have invented certain new and useful Improvements in Fire-Alarm Systems; and we do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

This invention relates to certain improvements in that class of fire-alarm systems and to the private boxes employed therein which is referred to in my prior applications, Nos. 277,807, 287,726, 287,083, and others.

The object of this invention is to secure a more perfect efficiency of service; and it consists in the improved fire-alarm box and fire-alarm system having the arrangements and combinations of parts substantially as will be hereinafter set forth, and finally embodied in the clauses of the claims.

Referring to the accompanying drawings, 30 embraced in two sheets, in which like letters indicate corresponding parts in each of the several figures, Figure 1 is a front elevation illustrating the improved box in its preferred construction and the fire-alarm system of which it forms a part. Fig. 2 is a detail plan of a circuit-changer employed in said box, and Fig. 3 is a detail view of the galvanometer employed with the fire-alarm box. Fig. 1^a, Sheet 2, is a similar view to Fig. 1, showing a 35 modified construction and arrangement of the box mechanism and system of which it forms a part. Fig. 2^a is a detail plan of the circuit-wheel of a preferred construction and co-operating parts, and Fig. 3^a is a central section of said circuit-wheel.

In said drawings, *a* indicates a casing or box, preferably of wood, with a glass or glazed front door, in which box the working parts are arranged and protected from dust and

the effects of the weather, and through which 50 door the said working parts may be seen and the handle for operating said working parts may be grasped, in the event of a fire, after fracturing the glass, and manipulated to produce a movement of the circuit-changing 55 mechanisms. Of said circuit-changing mechanisms *b* indicates a main shaft on which the handle (in the preferred construction a crank *c*) for winding the motor is arranged. Said shaft has its bearings in a metal frame *d*, as 60 do most of the other working parts for operating the circuit-wheel. On said shaft *b* is arranged a spring *e*, adapted to be wound up under the influence of the crank when the latter is turned, said spring having its center bearing on said shaft and its outer bearing on the frame or other suitable fixture. On said shaft is also arranged a loose cog-wheel *f*, adapted to move independent of the shaft. Said cog-wheel is provided with a 70 spring-actuated pawl *g*, which engages the ratchet-wheel *h*, fixed on said shaft to move therewith.

The cog-wheel *f* engages a pinion *h'*, by means of which the power exerted by the 75 spring is transmitted to a cog-wheel *i* on the circuit-wheel shaft *j*, by which the latter is turned and with it the circuit-wheel *k*. The cog-wheel *i* engages a pinion *l* on a shaft or arbor *m*, having thereon a suitable governor 80 or regulator, which may consist of an escape-wheel *n* and escapement-pawl *o*.

The circuit-wheel *k* consists of two parts *p* *q*, one of which controls the operation of an extension *r'* of the main fire-alarm circuit *r*, 85 so that an alarm of fire may be made on the bells, gongs, &c., thereon, and the other said part engages another extension or shunt *u* of or an auxiliary to the said main circuit, connecting with the nearest engine-house to 90 transmit the alarm thereto before the same is transmitted over the main circuit. The part *p* of said circuit-wheel *k* may be integral with or insulated from the other part, and is provided with a series or plurality of circuit-changing projections or parts for making and breaking the circuit of the extension-wires *r'*, 95 connecting with the ordinary municipal or

street box *v* of the main fire-alarm system and controlling the escapement therein, whereby the circuit-wheel of said municipal or street box will be operated only after the extension-wire has been broken a series or plurality of times at the private box, substantially as described in certain of the applications heretofore referred to.

The part *q* of the circuit-wheel has thereon similar contact-points for making or breaking the circuit, the said points corresponding to the distinguishing number of the box, so that when a fire occurs and the motor is set in operation an alarm will be sent over the engine-house extension or auxiliary *u* immediately while the escapement of the main box is yet being released, so that the exact location of the fire may be known at the nearest engine-house *E* before the general alarm is sounded. The bell *w* of the said engine-house may be on an auxiliary circuit independent of the main fire-alarm circuit; but we prefer to operate the said bell by means of a shunt wire and magnet arranged on the main circuit, and thus dispense with the use of local batteries, which are open to the manipulation of inexpert operators or attendants. The contact springs or terminals *s* for engaging the circuit-wheel parts are of any ordinary construction or arrangement, the springs being preferably arranged side by side on a block *t* of suitable insulating material.

In operating the improved system in accordance with our improvements the motor in the private box is actuated by turning the hand-crank therein so that the parts of the circuit-wheel are operated simultaneously. The extension-line *r'* is then broken to effect a step-by-step movement of the escapement in the district box, and at the same time the wire *u* direct to the nearest engine-house is broken and an alarm transmitted to said engine-house on the bell *3* before the regular alarm on the bell or gong *4* is sent in over the main circuit. The auxiliary circuit *u* may be independent of the main circuit *r*, and may be controlled by a battery *5* at the engine-house, as in Fig. 1^a; but we prefer the arrangement shown in Fig. 1, in which the single battery *5* at the fire-alarm headquarters or central office *C* controls the whole system.

In the preferred construction the normal course of the current is as follows: Starting from the battery at the headquarters *C*, the current passes over the main line *r* to the district box *D B*. From thence it passes over the shunt *r'* to the private box *P B*, and from thence back over said shunt to the district box. It then passes to the engine-house *E*, where it is again shunted and caused to pass over the wire *u*, back to the private box, where it may be broken at *s q*. After passing back again to the engine-house and through the bell mechanism *3*, the current finally returns to the battery at headquarters. When the auxiliary is broken at the

terminals *s p*, the current is forced through the electro-magnet of armature *6* at the engine-house. Said magnet being wound with wires of greater resistance than the main-line wires, the current normally takes the longer course over the shunt *u*; but when the latter is broken at the private box the said magnet is magnetized and its armature attracted.

To enable a person at the private box to understand or know whether or not the alarm has been sent from the district box, we employ a galvanometer *10* and arrange the same on a shunt *13* of the shunt *r'*, so that when the latter shunt is broken at terminals *11 12* by pushing on the button *14* the current will be forced through the magnet of the galvanometer, and when the alarm is sent out from the district box the magnet will be influenced and the needle turned, so that the fact will be apparent to the person at said private box, and a second alarm will not be sent out.

Having thus described the invention, what we claim as new is—

1. The improved fire-alarm system, combining therein a main circuit having a central office *C* and its battery, a district alarm-box with its controlling-magnet, and a fire-engine house and its alarm mechanisms thereon, a shunt *r'*, extending around the said controlling-magnet and having a private box thereon, and an auxiliary line *u*, extending from said private box direct to said engine-house, whereby the alarm mechanism of said engine-house is affected to effect an immediate alarm prior to the transmission of an alarm to said engine-house over the main circuit, the said private box having a circuit-changer therein for changing the currents over said shunt and said auxiliary lines, substantially as set forth.

2. The improved fire-alarm system herein described, combining therein a main circuit having an engine-house with its alarm mechanisms and district box with its circuit-changing mechanisms and means for operating said mechanisms locally, and having a magnet controlling said circuit-changing mechanisms, a shunt extending around said controlling-magnet of said district box and having a private box thereon with circuit-changing mechanisms therein, and a direct line extending from said private box to said engine-house and controlled by the said circuit-changing mechanisms of the said private box, whereby an alarm may be transmitted to said engine-house direct before the regular alarm is received at said engine-house over the main line, substantially as set forth.

In testimony that we claim the foregoing we have hereunto set our hands this 17th day of July, 1889.

FREDERICK T. FEARAY.
JOHN SPEICHER.
